UNITED STATES PATENT OFFICE.

HOMER B. PAYNE, OF WINNETKA, ILLINOIS.

DESIGN FOR A COLOR-DISPLAY PANEL.

Application filed March 1, 1926. Serial No. 16,708. Term of patent 14 years.

To all whom it may concern:

Be it known that I, HOMER B. PAYNE, a citizen of the United States of America, and a resident of the village of Winnetka, county of Cook, and State of Illinois, whose residence address is No. 595 Elm Street, Winnetka, Illinois, have invented a new, original, and ornamental Design for a Color-Display Panel, of which the following is a specification, reference being had to the

accompanying drawings, forming a part thereof.

Fig. 1 is a front elevation of the color display panel. Fig. 2 is a side elevation thereof.

I claim:

The ornamental design for a color display panel, as shown.

HOMER B. PAYNE.
